FLUSH TOGGLE SWITCH ATTACHMENT

Robert E. Seaman, Lansing, Mich.

Application July 9, 1946, Serial No. 682,196

4 Claims. (Cl. 200—172)

1

This invention relates to an attachment for wall type toggle switches particularly but not exclusively adapted to facilitate operation of such switches by children unable to reach the switch in its normal location, and aims generally to improve such devices.

Particular objects of the invention, severally and interdependently, reside in the provision of a simple, inexpensive structure having a neat, high quality appearance; highly efficient and effective in its operation; easily applied, and which presents no surfaces apt to cause injury to one groping for the switch in darkness.

Further objects and advantages of the invention will be apparent from the following detailed description of the preferred embodiment of the invention shown in the accompanying drawings, in which:

Fig. 1 is a front view of the device attached to a wall switch, shown in broken outline.

Figs. 2 and 3 are sectional views taken on the lines 2—2 and 3—3 of Fig. 1, respectively, in the direction indicated by the arrows.

In the form of the invention shown in the drawings, the attachment comprises a supporting member 10 having mounting means 11 positioned to cooperate with the securing means 12 employed to hold the normal wall plate 13 in assembled relation to a wall type toggle switch.

In the adaptation shown, the wall type switch is of conventional flush mounted construction and comprises a toggle switch element 14, the toggle operator 15 of which swings in a vertical plane. As is usual in such devices, the switch 14 is mounted on a retaining strip 16 secured to an outlet box 17. In such installations it is customary to secure the wall plate 13 by counter-sunk so-called oval-headed screw means 12 threaded into the retaining strip 16 in a standard predetermined relation to the switch structure, and usually threaded through the strip for a considerable distance to provide tolerance for failure of the installer to mount the outlet box 17 flush with the wall surface, or his failure to mount the retaining strip in proper relation to the wall surface. The present invention preferably utilizes the length of the screw means 12, thus normally provided, to secure the attachment in place, making minor adjustments of the usual strip retaining screws 18, if this is necessary.

As is best shown in Fig. 1, the supporting member 10 is provided with a pivot member 20 and is formed to lie flat against the switch plate 13 with its pivot member 20 disposed laterally of and in predetermined spaced relation to the toggle

2

arm 15 of the switch 14. In the preferred embodiment, the supporting member 10 is of arcuate shape, has counter-sunk mounting screw receiving apertures 11 at its ends, and has its pivot 20 disposed midway of its length, thus adapting it for attachment to a standard vertically swinging wall type toggle switch of the kind having its cover plate 13 retained by a pair of screws 12 aligned at standard spacing in the plane of operation of the toggle member 15.

The pivot 20 preferably comprises a bearing surface 21 and a shank 22 separated by a shoulder 23 spaced a predetermined distance from its head 24, the shank 22 being adapted for securement in the supporting member 10 in any desired manner. In the form of Fig. 3, this securement is shown as effected by riveting-over of the end of the shank 22 in a counter-sunk recess in the rear of the supporting member 10, as illustrated at 20 22a.

Prior to the securement of the pivot 20 in the support 10, this pivot member is passed through the fulcrum point of the operating lever 25 which is drilled or otherwise journaled to fit the bearing surface 21 and swing freely thereon after securement of the pivot in the supporting member 10.

The operating lever 25 is a lever of the first class having one of its ends bifurcated as at 26 30 and positioned to embrace loosely the toggle operator 15 of the wall switch 14. As best shown in Fig. 1, its bifurcated end 26 has inturned prongs, preferably rounded, which contact the opposite sides of the toggle member 15 to avoid 35 binding of the bifurcated legs against the toggle and scratching or chipping thereof, and to adapt the device to fit toggle members of different thicknesses.

To the two ends of the lever 25 are secured pulls 40 27 and 28 terminating in pull rings or the like 29 and 30. In the preferred embodiment, the pulls are shown as single cords knotted in place, but any other form may be employed, for example the double cord type may be secured to the rings 45 29 and 30 by passing their loops therethrough and thereover, with their upper ends threaded through apertures 31 and 32 in the opposite ends of the lever 25 and knotted therebehind.

The various parts of the attachment may be 50 formed of any suitable material.

The pulls 27 and 28 are preferably formed of lightweight waxed or varnished cord, as fish line or the like, adapted to support a predetermined strain less than that required to bend the portions 55 10 or 25 of the attachment, or damage the

pivot 20 thereof. They will thus easily carry a pull, generally parallel with the wall, adequate to operate the switch, but an excessive or out-of-line pull on the cord 21 or 28, will cause breakage of the cord rather than bending or breakage of the other parts of the attachment. Further, the waxed or varnished character of the cord serves to preserve its initial strength without serious deterioration over a considerable period, and this type of cord is particularly resistant to soiling, and thus maintains for a long period a clean, attractive appearance. If desired a flexible plastic cord may be employed, suitably knobbed at its joint end, and adapted for assembly by threading and looping of its bight as above mentioned.

The supports 10 and lever 25 advantageously may be formed of polished aluminum having a thickness of about $\frac{1}{8}$ of an inch or so, or these parts may be formed of plastic, for example, having sufficient rigidity and strength to render the parts highly resistant to bending and breakage. The rings 29 and 39 may be of molded plastic or other material and of any suitable form, and may comprise luminous material, if desired. The pivot 20 may have a head of any desired shape, preferably one of rounded or counter-sunk type providing no sharp points or edges apt to injure the hand of one groping for the wall switch in the dark. To this same end, the members 10 and 25 have rounded edges and all edges and ends of the members are nicely finished as by smoothing, buffing and polishing, for example, such finish, with the simple and harmonious form of the structure, adding to its sightliness and high-quality appearance.

Depending on the materials of construction, the pivot 20 may be secured by riveting as shown, or otherwise. For example, it may have a threaded or self-tapping shank and be provided with a kerf or the like to receive a driving instrument if desired.

From the foregoing description, it will be apparent that the invention is not limited to the precise form shown, and that various modifications are contemplated within the scope of the appended claims.

I claim:

1. A device for attachment to a toggle wall switch of the type having a switch plate secured by two screws aligned with the plane of operation of its toggle element; said device comprising an arcuate support formed to lie flat against the switch plate and having at its ends screw holes positioned to align with the switch plate securing screws, a pivot carried by the central portion of said arcuate support, a lever of the first class carried by said pivot and swinging in a plane parallel to the plane of the switch plate, said lever having a bifurcated end terminating in inturned prongs in general alignment with said screw holes and positioned to embrace the toggle element of the wall switch when the attachment is mounted thereon, and pulls attached to the ends of said lever.

2. A device for attachment to a wall type toggle switch of the type provided with a toggle protruding through a flat removable switch plate; said

device comprising a support provided with aperture means positioned to align with and be held in place by the switch plate securing means of the switch, a pivot carried by said support and positioned to lie laterally of the toggle of the switch, a lever of the first class mounted on said pivot and swinging in a plane parallel to the plane of the switch plate, said lever having a bifurcated end adapted to embrace the toggle of the switch, and pull cords secured to the opposite ends of said lever whereby said lever may be swung in either direction about said pivot.

3. A device for attachment to a wall type toggle switch of the type provided with a toggle protruding through a flat removable switch plate; said device comprising a support provided with aperture means positioned to align with and be held in place by the switch plate securing means of the switch, a pivot carried by said support and positioned to lie laterally of the toggle of the switch, a lever of the first class mounted on said pivot and swinging in a plane parallel to the plane of the switch plate, said lever having a bifurcated end adapted to embrace the toggle of the switch, and pull cords secured to the opposite ends of said lever whereby said lever may be swung in either direction about said pivot, said pull cords attached respectively to the bifurcated end and to the opposite end of said lever and strong enough to operate the switch when pulled generally parallel with the wall but weak enough to break before damage to the other parts of the device if pulled excessively or at an excessive angle to the wall.

4. An attachment of the class described comprising an arcuate support having counter-sunk mounting apertures at its ends to provide for its flat securing to the plate of a toggle wall switch by the normal securing screws of said plate, said arcuate support having a pivot midway between said mounting apertures and positioned to lie laterally of the toggle of said switch, a first class lever carried by said pivot and swingable in a plane parallel to the plane of the switch plate, said lever having a bifurcated end aligned with said mounting apertures to embrace a toggle switch operator moving in the plane of said apertures, and pull cords connected to the opposite ends of said first class lever.
